UNITED STATES PATENT OFFICE.

EUGENE A. QUIMBY, OF HALEDON, NEW JERSEY.

ADVERTISING DEVICE.

1,265,380.

Specification of Letters Patent.

Patented May 7, 1918.

Application filed July 25, 1916. Serial No. 111,222.

To all whom it may concern:

Be it known that I, EUGENE A. QUIMBY, a citizen of the United States, residing at Haledon, in the county of Passaic and State New Jersey, have invented certain new and useful Improvements in Advertising Devices, of which the following is a specification.

My present invention relates to certain new and useful improvements in advertising devices; and as its primary object it contemplates the provision of an improved device of this character that includes means for rockably supporting an element in conjunction with the sign proper to be actuated by the jolting or swaying of the respective device upon which it is used.

A further object of my invention is to provide a device of the type in question that is extremely simple in construction, strong and durable, and highly practical from both the standpoint of the manufacturer and the standpoint of the user; and which, it is believed, may be manufactured at a comparatively low cost.

Various other objects and advantages will become apparent during the continuance of the following description.

These objects are accomplished by such means as are shown in their preferred form in the accompanying drawings, described in the following specification and then more specifically pointed out in the appended claims.

In the accompanying drawings wherein like characters designate like parts throughout the several views;

Figure 1 is a view in front elevation showing my invention as in its preferred embodiment;

Fig. 2 is a view in top plan showing the relative position of the movable member;

Fig. 3 is a cross sectional view taken on the line 3—3 of Fig. 1;

Fig. 4 is a view in detail of the movable member.

In reducing my invention to practice, I preferably provide a base or other suitable supporting structure, such as for instance, is designated by the numeral 10; that may be formed of any desirable material, and contains such illustration or sign, as desired. However, in the present embodiment, this base will be formed of a relatively thin and light metal or heavy card board, having its lower marginal edge bent

as indicated by the numeral 11 so as to form a shield 12 and a suitable receiving space or housing. As pointed out hereinbefore, the base 10 may be provided with any suitable illustration or sign, such for instance as an advertisement of "Fairy soap." The distinguishing characteristic of this soap is that it floats and therefore, the member 13, in the present instance may be formed to resemble the contour of a cake of this particular soap and mounted so as to give the impression to the observer, that it is floating.

The member 13 itself, may be constructed of any desirable material, such for instance as card board or the like, and in view of such circumstance, I do not desire to limit myself to any specific form. With a view of supporting this member, in a manner such as set forth above, I first provide the base 10 with a suitable vibratory, rectilinear and horizontal supporting member or track which, in the present embodiment, is shown in the form of a strand of resilient wire 14 having its ends secured in the base so as to space its intermediate portion therefrom. The supporting member 14 is preferably arranged between the base 10 and the bent portion or shield 12 thereof whereby it will be obscured from the view of the observer.

A branch member or carriage, such as designated in its entirety by the numeral 15, carries a supporting pin or pivot 16, which in turn connects with the member 13 in the manner shown; while a bushing 17 is arranged between the said member and the branch member 15 so as to retain the same in spaced relation to the carriage. The leg portions 18 of the carriage 15 are suitably curved, as at 19, adjacent their lower ends to form bearing portions which may be effectually engaged with the supporting member 14. It is contemplated to arrange the carriage 15 substantially intermediate the ends of the supporting member 14, whereby the greatest amount of resiliency of the latter may be utilized, and at the same time support the member 13 in a position whereby its lower edge will normally overlap the upper edge of the flange or shield 12 of the base, so as to completely hide the legs or downwardly diverging branches 18 of the carriage 15.

This type of device is readily applicable for use in connection with street car advertising, since the jar and swaying of the car

would cause the members 13 to be rocked in a desired manner so as to give the same an appearance as if it were floating. The member 13 is freely rotatable with respect to the branch member 15, to a certain extent, and this movement combined with the vibrations of the supporting member 14 causes the carriage 15 to have a gliding movement along the track 14, such movement being in opposite directions, according to whether the car is moving up grade or down grade.

Furthermore, it is pointed out that the member 13 may be used under varying conditions, inasmuch as the particular function 15 of the same is to attract attention by its movement. Thus it is to be fully understood that I do not limit myself to the present embodiment in any degree except as defined by the claims.

20 The branch member 15 in the present embodiment has its leg portions 18 interconnected as shown to form an eye 20 for receiving the supporting pin 16 although it is to be understood of course, that I do not limit 25 myself to this specific construction.

From the foregoing, it is believed that the advantages and novel features of my invention will be readily understood and, therefore, further detail description is deemed 30 unnecessary.

In reducing my invention to practice, I find that the form referred to herein as the most practical and preferred embodiment is the most efficient, but realizing that certain 35 conditions will necessarily vary in concurrence with the adoption of my device, I desire to emphasize the fact that various minor changes in the details of construction and in the proportion of parts may be resorted to when required without sacrificing any of the advantages of my invention as defined in the appended claims.

Having thus fully described my invention, what I claim as new and desire to secure by Letters Patent is:—

1. An advertising device comprising a body adapted to have an advertisement displayed thereon, a substantially horizontal track supported by said body and being 50 vibratory with relation to said body, a carriage secured to said track and movable therealong, and an advertising element mounted on said carriage so as to move therewith and to move with relation thereto.

55 2. An advertising sign adapted to be carried by a car and comprising a sheet or plate having its lower portion turned upward so as to provide a flange and a housing, a track within said housing, a carriage engaged with 60 said track and movable therealong, said carriage extending above the upper edge of said

housing, and an advertising element supported by said carriage and having its lower edge in coöperative relation with the upper edge of said flange so as to hide said carriage 65 from view, whereby the said advertising element has the appearance of floating from side to side of said sheet or plate as the car moves up or down grade.

3. The combination of a sign member, a length of resilient wire having its ends secured to said sign member and having its intermediate portion spaced therefrom, a shield connected to said sign member and hiding said wire from view, a carriage movably secured to said wire and extending upward therefrom, and a sign element secured to the upper portion of said carriage and being movable with said carriage and also being movable with relation thereto.

4. An advertising sign adapted to be carried by a car and comprising a sign member having its lower end formed with a housing the upper edge of which is substantially horizontal when the car is on a horizontal track, a track in said housing and being also substantially horizontal when the car is on a horizontal track, a carriage supported by said track and extending upward therefrom above the upper edge of said housing, and a sign element supported by the upper end of said carriage and extending downward below the upper edge of said housing, whereby, the said advertising element is movable with said carriage by the means of gravity 95 and the vibration of said track when the car moves up or down grade; the said carriage being hidden by said housing and said sign element.

5. A sign comprising a base sign member, a track supported in approximately horizontal position thereon, a carriage having downwardly diverging branches which engage with said track and extending upward therefrom, a pivot carried by said downwardly diverging branches, an advertising device supported by said pivot and movable thereabout, and means coöperating with said advertising member for completely hiding the said carriage and track, whereby the said advertising element moves across said advertising member and also rocks with relation thereto when said track is inclined from the horizontal position and is caused to vibrate.

In testimony whereof I affix my signature in presence of two witnesses.

EUGENE A. QUIMBY.
